United States Patent Office

Des. 178,179
Patented July 3, 1956

178,179

PAIR OF SUNGLASSES

Jack F. Fleming, Summit, N. J., assignor to Curtiss-Wright Corporation, a corporation of Delaware

Application December 7, 1953, Serial No. 27,944

Term of patent 14 years

(Cl. D57—1)

The single figure is a front perspective view of a pair of sunglasses showing my design.

I claim:

The ornamental design for a pair of sunglasses, substantially as shown.
